UNITED STATES PATENT OFFICE.

AUGUST W. WARSEN, OF NEW YORK, N. Y.

CRUSHER.

1,148,345.

Specification of Letters Patent.

Patented July 27, 1915.

Application filed May 20, 1914, Serial No. 839,780. Renewed June 18, 1915. Serial No. 34,962.

To all whom it may concern:

Be it known that I, AUGUST W. WARSEN, a citizen of the United States, and a resident of the city of New York, borough of Brooklyn, in the county of Kings and State of New York, have invented a new and Improved Crusher, of which the following is a full, clear, and exact description.

My invention relates to crushers of the rotary type; and the object thereof is to provide a simple, strong, inexpensive and efficient crusher in which the translating roller is prevented from vibration during the crushing.

With the above and other objects in view, the nature of which will more fully appear as the description proceeds, the invention consists in the novel construction, combination and arrangement of parts as herein fully described, illustrated and claimed.

In the accompanying drawings, forming part of the specification, similar characters of reference indicate corresponding parts in all the views and—

Figure 1 is a side elevation of a roller crusher embodying my invention; Fig. 2 is a plan view of the washer interposed between the anti-vibration device and the frame of the crusher; Fig. 3 is a horizontal section through the frame of a crusher showing a modified structure of the anti-vibration means; and Fig. 4 is an elevation of the washer interposed between the translating bearing of the crushing roller and the anti-vibrating device.

In the roller crushers in use at present, the translating roller is maintained against the stationary roller by a series of compression springs mounted with their axes parallel to the axis of the guide bolt which controls the compression of the springs; and due to this position of the springs, when they are once set into vibration they continue to vibrate and, therefore, interfere with the crushing of the material. Furthermore, this continuous vibration, due to the harmonic motion set in the springs, is transmitted to the frame and other parts of the crusher and thereby reduces its life.

To obviate the above objections and prolong the life of the crusher, and also to obtain better final products of crushing, I provide an anti-vibration device for the translating roller, which consists of a first-class lever formed of a pair of contacting arms 5 and 6 (see Fig. 1) spaced at one end; and adja-

cent that spaced end they are fulcrumed to each other by providing a recess 7 in the arm 5, which is engaged by a projection 8 in arm 6. The two arms are maintained against each other by compression springs 9 mounted on each side of the arms 5 and 6 on bolts 10 provided at the contacting ends of the arms 5 and 6, said bolts 10 having their axes at right angles to the axis of the fulcrum of the arms 5 and 6. The arms 5 and 6 at their spaced end are each provided with alining apertures 11 the axis of which is parallel to the axis of the bolts 10 and through which aperture projects the guide bolt 12 which is connected to the bearings 13 slidably mounted in a frame 14, said bearings 13, of which only one is shown, carrying a translating roller 15, the movement of which is controlled by the compression springs 9.

Positioned intermediate the anti-vibrating means and the frame 14 is a block or washer 16 mounted on the guide bolt 12 and provided on the side contacting with the frame 80 with a key 17 engaging a keyway 18 provided in the frame, whereby said washer is prevented from turning on the bolt 12. The washer 16, on the side facing the arm 5, is provided with a recess 19 the axis of which 85 is parallel to the axis of the fulcrum of the arms 5 and 6, and which is preferably in a horizontal plane with the axis of the guide bolt 12. The arm 5 is provided with a projection 20 engaging the recess 19 of the washer 16, whereby said arm 5 is fulcrumed on said washer, the fulcrum of the arm 5 being lower than the common fulcrum of the arms 5 and 6. The arms 5 and 6 are maintained against the washer 16 by a nut 95 21, between which nut and the arm 6 a washer 22 is provided to reduce the friction therebetween through the movement of the arm 6.

The compression springs 9 will maintain 100 the roller 15 against a stationary roller 23, their compression being so adjusted that when the two rollers 15 and 23 are in proper position the upper parts of the arms 5 and 6 are in contact, *i. e.*, the compression springs 105 9 cannot expand any farther. When the roller 15 is displaced from the roller 23 by some cause, the arms 5 and 6 are separated, the arm 6 moving on its fulcrum, *i. e.*, the projection 8 turns in the recess 7. Simultaneously the arm 5 will also fulcrum on the washer 16 and the springs 9 will be com-

pressed. As soon as the strain separating the rollers is removed, the springs 9 will bring the arms 5 and 6 into contact, thus restoring the roller 15 to its original position; and any vibration set up in the springs 9 cannot move the arms 5 any farther than to bring them in operative contact. Furthermore, by providing oppositely acting springs the harmonic motion caused by vibration therein is counteracted. The position of the springs 9 on the arms 5 and 6, furthermore, increases the resistance to vibration due to the leverage resulting from the distance of said springs 9 from the 15 guide bolt 12, where the stress takes place.

In the modified structure shown in Fig. 3, the first-class lever is placed between a slideable bearing 24 and a bolt 25 carried by a frame 26 of the crusher. Contacting arms 20 27 and 28 are in this case positioned horizontally to one side of the frame, the arms being maintained together by springs 29 mounted on bolts 30, which bolts are preferably carried by the arm 27 at the contacting 25 end. At the spaced end the arm 27 is provided with a lateral projection 31 engaged by the bolt 25, while the arm 28 is provided at the spaced end with a projection 32 engaged in a recess 33 provided in a sliding 30 block or washer 34 positioned between the bearing 24 and the arm 28. The projection 32 forms the fulcrum for the arm 28 on the washer 34. It will be noted that the axis of the fulcrum for the arm 28 is perpendicular 35 to the axis of the bolts 30 carrying the springs 29. The arm 27 is also fulcrumed in the arm 28 by engaging the end 35 of the arm 27 adjacent the lateral projection 31 into a recess 36 provided in the arm 28. 40 It will be noted that the fulcrum of the arm 27 is offset from the fulcrum of the arm 28 but their axes are parallel, the fulcrum of the arm 28 being in alinement with the axis of the bolt 25, a displacement of the bearing 24 in the direction of the arrow shown 45 in Fig. 3 will cause the separation of the arms 27 and 28, for the reasons stated for Fig. 1, and the effect produced by the springs 29 will be similar to what has been 50 described for the springs 9.

From the foregoing description, taken in connection with the accompanying drawings, the advantage of the construction and operation of the device shown will be readily understood by those skilled in the art to which the invention pertains; and while I have described the principle of operation,

together with the device which I now consider to be the best embodiment thereof, I desire to have it understood that the device 60 shown is merely illustrative and that such changes may be made when desired as are within the scope of the appended claims.

Having thus described my invention, I claim as new and desire to secure by Letters 65 Patent:

1. In a crusher, a frame, a fixed roller thereon, a translating roller coacting with the fixed roller, resilient means for maintaining the translating roller against the 70 fixed roller, and a pair of fulcrumed arms positioned between the resilient means and the translating roller.

2. In a crusher, a frame, a fixed roller thereon, a second roller coacting with the 75 fixed roller, bearings mounted to slide in said frame carrying said second roller, resilient means associated with each bearing, and a pair of relatively movable arms positioned between the bearing and the 80 resilient means, said arms forming a lever of the first class.

3. In a crusher, a frame, a fixed roller thereon, a translating roller coacting with the fixed roller, resilient means for maintaining the translating roller against the 85 fixed roller, and a lever of the first class formed of two relatively movable arms positioned between the resilient means and the translating roller, each of said arms of said 90 lever forming also a lever of the first class.

4. The combination with a roller crusher having a translating roller of an anti-vibrating device for the translating roller comprising, a pair of relatively movable 95 arms associated with the translating roller and a resilient member normally maintaining said arms together.

5. The combination of a roller crusher having a translating roller of an anti-vibrating device for the translating roller comprising, a pair of relatively movable arms associated with the translating roller, each of said arms forming a lever of the 100 first class having a common fulcrum, and resilient means normally maintaining said arms together.

In testimony whereof I have signed my name to this specification in the presence of two subscribing witnesses.

AUGUST W. WARSEN.
